CLAIM

The ornamental design for a combined fence and gate system, as shown and described.

DESCRIPTION

FIG. 1 is a perspective view of a combined fence and gate system of the present invention; and,

FIG. 2 is a perspective view of a combined fence and gate system of the present invention.

The broken line showing of FIGS. 1 and 2 are for the purpose of illustration of the holes in the square plates and form no part of the claimed design.

1 Claim, 2 Drawing Sheets

FIG. 1

FIG. 2
